UNITED STATES PATENT OFFICE.

JACOB M. OLINGER, OF SPRINGFIELD, OHIO.

TROLLEY.

1,114,283.

Specification of Letters Patent. Patented Oct. 20, 1914.

Application filed May 14, 1913. Serial No. 767,568.

To all whom it may concern:

Be it known that I, JACOB M. OLINGER, a citizen of the United States, residing at Springfield, in the county of Clark and State of Ohio, have invented certain new and useful Improvements in Trolleys, of which the following is a specification.

My invention relates to improvements in trolleys for electric railways, particularly to that type of the trolley employing a quickly detachable pole.

The object of my invention is to improve upon the connections heretofore employed for attaching the trolley-pole to the stand so that the operation of removing and replacing the poles may be more simply and easily accomplished and also to provide connections which will be more simple in construction, effective in operation, and cheaper to manufacture.

The invention consists in the constructions hereinafter described and set forth in the claims.

In the accompanying drawings,—Figure 1 is a front elevation of a trolley embodying my improvements, the pole being shown broken away. Fig. 2 is a rear elevation of a portion of the same. Fig. 3 is a front elevation of a portion of the same, the trolley-pole and its clamp shown in Fig. 1 being removed. Fig. 4 is a side elevation of a portion of the pole and its clamp. Fig. 5 is a vertical section of some of the parts shown in Fig. 1, the section being on the line 5—5 with the swiveled support removed. Fig. 6 is a side elevation of the device with the pole broken away. Fig. 7 is a transverse section on the line 7—7 of Fig. 5. Fig. 8 is a detail of a spring contact between certain of the parts.

Like parts are represented by similar characters of reference throughout the several views.

In the said drawings, 1 represents the part to which the trolley is connected such as the roof of an electric car. 2 is the base of the trolley-stand upon which is swivelly mounted the usual standard 3. The supporting arm of the trolley, represented by 4, has its lower bifurcated end, 4^a, pivotally connected to the standard 3 through the medium of the pivot pins 5 which extend through the bifurcated portion of the arm and also integrally formed bosses 6 on the stand. The bifurcated members of the arm 4 are projected below the pivotal connec-

tions just referred to and have pivotally connected therewith springs 7 which extend rearwardly and are adjustably connected with the cross-bar 8 attached to the rods 9 which are supported by and project rearwardly from the standard 3; these springs serving to normally hold the arm and the supported pole in operative position, the movement being limited by a bar 10 extending between and formed integrally with the bifurcated members 4^a of the arm. The construction as thus far described is one which is well-known and has been in common use.

The rear side of the arm above the bifurcated portion thereof is provided with a pair of spaced strengthening ribs 11. Pivotally connected to these strengthening ribs just above the bifurcated portion of the arm is a collar 12, said collar being located on the forward side of the arm and having a rearwardly projecting ear 13, which extends through a slotted opening 14 in the arm and is perforated to receive a pin 15, by which it is pivotally connected to said ribs. The trolley-pole 16 has secured to its lower end the two members 17 and 18 of a clamp, these clamping members being secured together by the clamping bolts 19 which extend through registered laterally projecting ears on the respective clamping members. The inner clamping member 17 has a downwardly projecting trunnion, 20, which is received in the collar 12. The upper rear side of the clamping member 17 also has a rearwardly extending projection 21 having its rear end provided with a down-turned lip 22. The upper end of the arm has a slotted opening 23, of substantially the same width as the projection 21 and of a height sufficient to permit the said projection 21 and its lip 22 to be inserted therein.

Slidably connected to the rear side of the arm 4 just above the opening 23 and between the ribs 11, is a latch-plate 24; said latch-plate being provided with a slotted opening 25, through which extends a bolt 26, a spring 27 being inserted between the nut 28 of said bolt and the washer 29 adjacent the latch-plate, so that said plate will be held in yielding contact with the arm. The lower end of the latch-plate has a forwardly extending flange, 30, adapted, when the latch-plate is thrown to operative position, to enter the slotted opening 23 of the arm and form a lock.

The operation of the device is as follows: In placing the pole in position, the trunnion 20 is first inserted in the collar 12. The projection 21 and its lip 22 are then inserted through the opening 23 and the pole allowed to drop to the position shown in Fig. 5, which allows the lip 22 to hook itself on the rear side of the arm below the opening. The latch 24 is then pushed downwardly until the locking flange 30 coincides with the opening 23, whereupon the spring will force it into the opening and thus form a bar against the removal of the pole. When it is desired to remove the pole for any reason, the operator presses forwardly upon the upper extension 24^a of the latch-plate until the flange 30 is removed from the opening and then pulls the latch-plate up until the flange 30 rests against the rear side of the arm, where it will be held by the tension of the spring. By then raising the pole slightly, the projection 21 and its lip 22 may be removed from the opening 23, the collar 12 rocking to permit of this movement; the opening 14 being slotted to permit of this rocking movement of the collar.

In order that close contact may be made between the parts to prevent arcing, there is riveted to the forward side of the arm a spring-plate 31, preferably of phosphor-bronze. The upper end of this plate is bent rearwardly as indicated at 32 and thence downwardly as indicated at 33; these parts 32 and 33 being extended through the opening 23 so as to lie along the lower edge of the opening and also along the rear side of the arm which is below the opening. Normally, the portion 33 projects rearwardly at a slight angle as shown in Fig. 8. When the projection 21 and its lip 22 are inserted in position, however, the portion 33 will be sprung against the wall of the arm but its resiliency will cause it to lie at all times against the lip 22 so that if the fit between these parts is not accurate, there will nevertheless be a close electrical contact between them by reason of this spring. By this construction it will be seen that the pole may be quickly removed and replaced without the use of tools and without any undue exertion upon the part of the operator, such as is required where springs are employed to hold the pole in locked position such as illustrated in my former Patent No. 840,649, dated January 8th, 1907, which employs a stiff spring to hold the inter-engaging parts in engagement, which spring must be compressed when a pole is removed or inserted, and necessitates considerable labor upon the part of the operator.

Having thus described my invention, I claim:

1. In a trolley, a pivoted supporting arm, a pole, and devices for detachably connecting said pole to said arm, said devices com-

prising a projecting part on said pole adapted to be extended through an opening in said arm and so formed as to be caused to engage the opposite side thereof by a movement of said pole relatively to said arm, together with means for locking said part against displacement. 70

2. In a trolley, a pivoted supporting arm, a pole, and devices for detachably connecting said pole to said arm, said devices comprising a hook-shaped projection on one of said parts extended into an opening in the other of said parts and then caused to engage the opposite side thereof by a movement of one of said parts relatively to the other together with means for locking said hook-shaped projection in said opening. 75

3. In a trolley, a pivoted supporting arm, a pole, and devices for detachably connecting said pole to said arm, said devices comprising a hook-shaped projection on said pole extended into an opening in said arm and then caused to engage the opposite side of said arm by a movement of said pole relatively to said arm together with means for locking said hook-shaped projection in said opening. 80

4. In a trolley, a pivoted supporting arm, a pole, means on said arm for supporting the lower end of said pole, said arm having an opening therein, a hook-shaped projection on said pole adapted to be extended through said opening and then caused to engage the opposite side of said arm by a movement of said pole relatively to said arm, and a spring-pressed latch on said arm adapted to enter said opening above said projection to lock the same to said arm. 90

5. In a trolley, a pivoted supporting arm, a pole, a pivoted support for the lower end of said pole, said arm having an opening, a hook-shaped projection on said pole adapted to enter said opening, and a latch on said arm for locking said projection in said opening. 105

6. In a trolley, a pivoted supporting arm, a pole, a socket pivotally connected with said arm to support the lower end of said pole, said arm having an opening, and a hook-shaped projection on said pole adapted to be extended into said opening, together with means for locking said projection in said opening. 115

7. In a trolley, a pivoted supporting arm, a pole, a clamp on the lower end of said pole, and devices for detachably connecting said pole and clamp to said arm, said devices comprising a hook-shaped projection on said clamp and an opening in said arm to receive said hook-shaped projection, together with means for locking said projection in said opening. 120

8. In a trolley, a pivoted supporting arm, a pole, a clamp on the lower end of said pole, a trunnion on the lower end of said 130

clamp, a collar pivotally connected with said arm adapted to receive said trunnion, a hook-shaped projection on said clamp, said arm having an opening to receive said hook-shaped projection, and means for locking said hook-shaped projection in said opening.

9. In a trolley, a pivoted supporting arm, a pole, devices for detachably connecting said pole to said arm, said devices comprising a hook-shaped projection on said pole extended into an opening in said arm, and a spring plate connected to said arm and extending through said opening so as to lie between said arm and said projection.

10. In a trolley, a pivoted supporting arm, a pole, devices for detachably connecting

said pole to said arm, said devices comprising a projection on said pole extended through an opening in said arm and so formed as to engage with the opposite side 20 thereof, and a spring plate connected with said arm and having its free end also extended through said opening between said projection and arm to form an electrical connection between said pole and arm. 25

In testimony whereof, I have hereunto set my hand this 30th day of April, 1913.

JACOB M. OLINGER.
